Inventor:

Siegmund Loewe

by C. A. Sprague. Atty.

UNITED STATES PATENT OFFICE

SIEGMUND LOEWE, OF BERLIN, GERMANY, ASSIGNEE TO WESTERN ELECTRIC COMPANY, INCORPORATED, OF NEW YORK, N. Y., A CORPORATION OF NEW YORK.

THERMIONIC TRANSLATING DEVICE.

Application filed March 19, 1921. Serial No. 453,842.

(GRANTED UNDER THE PROVISIONS OF THE ACT OF MARCH 3, 1921, 41 STAT. L., 1318.)

To all whom it may concern:

Be it known that I, SIEGMUND LOEWE, a citizen of the German Republic, residing at Berlin, Germany, have invented certain new and useful Improvements in Thermionic Translating Devices (for which I have filed an application in Germany, L-47,383, October 31, 1918, Pat. No. 357,822), of which the following is a full, clear, concise, and exact description.

This invention relates to methods of converting or amplifying currents and potentials, or modulating carrier waves in accordance with signals; and to apparatus for carrying out such methods. In one form of embodiment of the invention, two vacuum tubes each provided with a grid, which grids are excited in opposite phases, is made use of for stepping up or down the current or potential of a direct or alternating current. Similar apparatus is applied for the purpose of producing high frequency waves modulated in accordance with speech or other alternating or fluctuating currents. It is within the scope of the invention to transform electrical currents in any manner into other currents by means of apparatus hereinafter described and illustrated in the drawing or equivalent apparatus.

The invention comprises improvements upon the disclosure of U. S. patent to Langmuir, No. 1,273,626, patented July 23, 1918, which describes apparatus serving to convert direct current into current of other potential by the alternate charge and discharge of a device for storing of energy. This invention is an extension of that principle and modifies the apparatus so that the auxiliary energy necessary for the conversion is generated and applied in a special way. The apparatus is more useful in that it can be used not only for a converting rectifier, but also for changing an alternating current to an alternating current of another potential.

One object of the invention is to provide an arrangement whereby direct current of one voltage may be stepped up in voltage to direct current of a higher voltage. A further object of the invention is to provide a voltage-transforming arrangement for direct current in which the energy of increased voltage may vary in accordance with a signal or other control energy.

Referring to the drawing, Fig. 1 is a diagram showing the general system, while Fig. 2 shows an embodiment thereof.

The apparatus constituting the invention is shown in Fig. 1 applied to direct current transformation. 1 and 2 are the lines of the network between which are connected a vacuum tube 3 with cathode 4, grid 5, and anode 6 in series with the primary winding 7 of the transformer. The secondary winding 8 of the transformer which possesses a greater or less number of turns according to whether a step-up or step-down transformation of the potential or the current is desired, can be connected with one terminal with the line 2, so as to constitute an auto-transformer, if desired. It is preferred, however, to use a two-winding transformer with no other connections than a common lead between the cathodes of the vacuum tubes. It is likewise connected to a storage condenser 13 and the output line through a vacuum tube 9 with anode 10, grid 11 and cathode 12 (in some cases a heated filamentary electron emitting cathode). Grids 5 and 11 are now arranged so that they have opposite phases. This is done most simply by means of a coil 14, one point of which is properly selected, and is connected with the two cathodes 4 and 12 respectively, and its terminals connected to the grids 5 and 11, in order to determine the potential of the grids 5 and 11 compared to the two cathodes 4 and 12. The high-frequency oscillations of a known type of system for the generation of electric oscillations comprising vacuum tube 16, anode circuit 17, and grid circuit 18, with glowing cathode 19, is now brought to bear by inductive coupling on coil 14. This oscillation generator may be of any well known type and is illustrated as a type having tuned grid and plate circuits 17 and 18.

By means of the above described arrangement, the use of any auxiliary energy, either in the form of alternating or direct current connected by a switching device, is wholly eliminated. The apparatus operates automatically. It will be connected with the lines 1 and 2 to the terminals of the source of current which is connected to be transformed and will supply the desired converted current directly to the work circuit.

If a heated cathode is used, it can be connected in series with or parallel to the line 1,

2 or heated by any other suitable source. This is true of all the cathodes of the system. The anode potential of the vacuum tube 16 is the same as that of the vacuum tube 3.

If the apparatus is to be used for changing the amplitude of the current or potential of an alternating wave current, it will be best to superpose the wave current on the grid circuit 18 of tube 16. In this way fluctuations of potential occur on the output line which are very greatly increased and are entirely in synchronism. In this case it is best to select condenser 13 as small as possible or to omit it entirely. In place of the work circuit, a telephone receiver can be connected for reception of the amplified energy or the grid circuit of the transmitting tube can be connected at this place for the purpose of wireless telephony, or the increased potential for fluctuations can be made to affect the transmitter in any way whatever. It is well known that one of the main difficulties in modulating the generators at continuous wave stations by microphone currents consists in the fact that the voltage amplitudes directly produced by the microphone are too small in comparison with the high frequency potentials to energetically influence the amplitude of the continuous waves.

In Fig. 2 a wireless telephone circuit using the apparatus according to Fig. 1 is illustrated in detail. This circuit is intended to be used for radiating carrier waves modulated in accordance with speech waves.

The vacuum tube 3 and the primary winding 7 of the transformer are in this case also connected to the network lines 1 and 2, while the secondary winding 8 is connected through the vacuum tube 9 to the grid 20 of a high frequency oscillation generator transmitter 21 for producing continuous modulated oscillations. 22 is a fixed condenser which is shunted through a high ohmic or inductive resistance 23, and is connected in series in the grid circuit 24 which controls the anode circuit of tube 21 connected with the antenna. 25 is the source of the anode current of the transmitter which can be replaced by an apparatus like that in Fig. 1. The microphone current 26 acts directly on coil 14, but it could also be arranged as in Fig. 1, thereby avoiding the necessity of any other source, such as a local source.

Having described certain practical embodiments of the invention, the novel features thereof are defined in the appended claims.

60 What is claimed is:

1. In combination, a source of direct current, a variable impedance element in circuit therewith, a second circuit inductively connected to said first-mentioned circuit whereby variations in the current flowing in

said first circuit induces electromotive forces in said second circuit, and common means connected to said variable impedance element and to said second circuit for simultaneously controlling the impedances of said two circuits.

2. A series circuit including a source of direct current and a three-element electric discharge device having an anode and cathode by which said device is connected in said circuit and an impedance control element, a second circuit inductively related to said first circuit and including a second electric discharge device having a cathode and anode by which it is connected serially in said second circuit and a control element, and common means for controlling the potentials of said control elements relative to their respective associated cathodes.

3. In combination, a source of direct current, a transformer primary winding and a space discharge path in series therewith, a transformer secondary winding inductively coupled to said primary winding, a second space discharge path in series with said secondary winding and means for simultaneously controlling the impedances of both of said discharge paths in accordance with signals.

4. In combination, a source of alternating current, means for variably rectifying said alternating current in accordance with signals to produce a unidirectional electromotive force varying in accordance with said signals, a vacuum tube oscillator having an impedance control circuit and means for impressing said unidirectional electromotive force thereupon to control the amplitude of the oscillations produced by said oscillator.

5. In combination, a vacuum tube oscillator having an input circuit and an output circuit, a source of direct current, a transformer primary winding and a space discharge path in series therewith, a transformer secondary winding inductively coupled to said primary winding and connected in series through a second space discharge path to the input circuit of said oscillator, and means for simultaneously controlling the impedance of both of said discharge paths in accordance with signals.

6. A vacuum tube oscillator having an input circuit and an output circuit, a source of alternating current, means for variably rectifying said alternating current in accordance with signals to produce a signal varied unidirectional electromotive force and means for impressing said unidirectional electromotive force upon the input circuit of said oscillator.

In witness whereof, I hereunto subscribe my name this ninth day of February A. D., 1921.

DR. SIEGMUND LOEWE.
